UNITED STATES PATENT OFFICE.

SAMUEL R. SARGENT, OF CLEVELAND, OHIO, ASSIGNOR TO THE LAPHAM-DODGE COMPANY, OF SAME PLACE.

DESIGN FOR A WASH-BOARD.

SPECIFICATION forming part of Design No. 20,378, dated December 9, 1890.

Application filed October 2, 1890. Serial No. 366,907. Term of patent 14 years.

To all whom it may concern:

Be it known that I, SAMUEL R. SARGENT, a citizen of the United States, residing at Cleveland, in the county of Cuyahoga and State of Ohio, have invented and produced a new and original Design in Wash-Boards, of which the following is a specification, reference being had to the accompanying drawings, in which—

Figure 1 is a plain elevation of a wash-board which embodies my design, and Fig. 2 is a central longitudinal section of said board.

The leading feature of the design is the plain cylindrical roller at the lower edge of the corrugated rubbing-plate and the protector at the top of the board.

A represents the side pieces of the wash-board frame, which are straight and plain and have slightly-tapering lower extremities.

B is a cross-piece connecting the upper ends of the sides, and C is a plain-surfaced board laid between the upper ends of the sides and beneath the cross-piece B. At or near the lower edge of the board C and laid upon the same is another cross-piece D, which extends to the side pieces and forms a projecting ledge upon said board. Both cross-pieces B and D extend outward beyond the face of the sides and at their ends have inclines b d,

respectively tapering to the depth of the sides. The cross-piece B is substantially semi-cylindrical in cross-section, its surface upon the top and sides being curved transversely and its bottom flat. Above the said cross-piece B is the protector E. The protector has a plain surface throughout and extends the full width of the frame, and its sides retreat or slope slightly toward its upper edge.

G represents the rubbing board or plate, provided with corrugations running transversely or from side to side of the frame, the surface of which board is entirely within the outer surface of the frame, and H is a cylindrical roller set in the frame a slight distance from the corrugated plate and having a plain exterior which stands out beyond said corrugations, but within the adjacent surface of the sides.

What I claim as new, and desire to secure by Letters Patent, is—

The design for wash-boards, as herein shown and described.

SAMUEL R. SARGENT.
